UNITED STATES PATENT OFFICE

STERLING H. CAMPBELL, OF ST. LOUIS, MISSOURI, ASSIGNOR TO WESTERN RAILWAY EQUIPMENT COMPANY, OF ST. LOUIS, MISSOURI, A CORPORATION OF MISSOURI

RETAINING VALVE FASTENING

Application filed May 2, 1929. Serial No. 359,975.

My invention relates to means for securing the retaining valve of an air brake system to the end of a railway car to which the system is applied. The object of the invention is to provide a device of simple construction for the purpose above mentioned.

In the accompanying drawings, which illustrate a retaining valve fastening made in accordance with my invention, Figure 1 is a front elevation of the detached device; Figure 2 is a side view showing the device in position on a car; and Figure 3 is a top plan view of the parts in Figure 2.

My retainer is formed from a single bar of metal, preferably square or approximately so in cross section. This bar is bent at its center to form an elongated loop 1 and a pair of diverging arms 2. The loop has its lower end closed by inwardly curved portions 3 at the junction of the loop with the arms. Portions 4 at the lower ends of the arms are bent over at right angles to the arms and are reduced to cylindrical form to provide studs 5 adapted to pass through the openings in the lugs 6 of the retaining valve 7.

The loop 1 is of sufficient length to permit of the necessary vertical adjustment of the valve relative to the car to which it is secured. One of the causes necessitating adjustment of the valve is the breaking off, due to vibration, of that part of the train pipe 14 which is threaded into the lower end 13 of the valve, as shown in dotted lines in Figure 2. Therefore the interior length of the loop 1 should be at least equal to the distance the pipe enters the valve plus the diameter of the bolt 8 to compensate for such breakage.

Through the loop 1 passes a bolt 8 provided with a collar 9 and riveted or otherwise fastened to the end 10 of a car, the device being firmly clamped between the collar and a nut 11 on the bolt. The studs 5 are threaded and provided with nuts 12 to secure the valve to the bracket.

Not only is my retaining valve fastening simple, strong, and easy of manufacture, but, owing to the fact that the ends of the arms 2 may be sprung toward or away from each other, it will readily accommodate itself to retaining valves in which the distance

between the lug holes varies. Furthermore, the loop may be made of any desired width so that the bolt 8 may be of sufficient size to furnish a firm and rigid support for the device.

Having fully described my invention, what I claim as new and desire to secure by Letters Patent of the United States is:

1. A retaining valve fastening comprising a bar bent to form a pair of spaced arms and an elongated central loop, each of said arms having its end turned over at right angles to form a stud to engage a retaining valve.

2. A retaining valve fastening comprising a bar bent to form a pair of arms and an elongated loop at its central portion and studs carried by said arms for engaging a retaining valve.

3. A retaining valve fastening comprising a bar bent to provide a pair of arms and an elongated central loop with closed ends, and studs forming extensions of said arms for engaging a retaining valve.

4. A retaining valve fastening comprising a bar of rectangular cross section bent to form a pair of spaced arms and an elongated central loop, each of said arms having its end turned over at right angles and reduced to form a cylindrical stud to engage a retaining valve.

In testimony whereof, I hereunto affix my signature, this 30th day of April, 1929.

STERLING H. CAMPBELL.
